UNITED STATES PATENT OFFICE.

ARCHIBALD R. STEPHEN, OF LODI, CALIFORNIA.

BELT CONTROL FOR PICKING TABLES.

Application filed December 20, 1921. Serial No. 523,702.

To all whom it may concern:

Be it known that I, ARCHIBALD R. STEPHEN, a citizen of the United States, residing at Lodi, county of San Joaquin, State 5 of California, have invented certain new and useful Improvements in Belt Controls for Picking Tables; and I do declare the following to be a full, clear, and exact description of the same, reference being had 10 to the accompanying drawings, and to the characters of reference marked thereon, which form a part of this application.

This invention relates to improvements in hand picking tables such as are used in picking over and sorting nuts, beans and 15 similar produce, and relates particularly with that type of picking table shown in my United States Patent No. 1,414,598, dated May 2, 1922, in which the table portion is 20 formed of a movable belt, whose movement is controlled by the operator or picker with the aid of a foot lever, the advantages of which are set forth in the above patent.

The principal object of the present invention is to provide an improved means 25 for controlling the movement of the belt, and at the same time allowing for the automatic taking up of the unavoidable shrinking and stretching of the belt, the length of 30 which is apt to vary considerably in the course of a day, depending on the relative humidity of the atmosphere at different times, and especially with the light flexible type of belt necessarily used.

A further object is to provide means 35 whereby the uneven stretching or tightening of the belt on either side may be readily taken care of without removing or handling the belt itself in any way.

Still another object is to provide means 40 whereby the amount or distance through which the foot lever itself must be moved to give a certain amount of slackness to the belt, and to also permit of the vertical 45 position of the foot-pad of the lever being altered without disturbing the position and setting of the belt. By this means the foot lever may be adjusted to suit the convenience of different persons, to insure efficient 50 operation in all cases.

A fourth object is to allow for altering the normal tension of the belt, to suit different conditions of operation.

I have found from experience that con- 55 siderable difficulty is had in getting a thin and even distribution of the produce on the

belt, as it comes from the hopper, especially with small material, such as seeds, which tend to pack behind the control gate of the hopper, and then discharge in irregular 60 quantities.

I have therefore devised, as another object of this invention, a means for preventing this packing of the produce, and insuring a steady and even flow thereof onto 65 the belt.

A further object of the invention is to produce a simple and inexpensive device and yet one which will be exceedingly effective for the purposes for which it is de- 70 signed.

These objects I accomplish by means of such structure and relative arrangement of parts as will fully appear by a perusal of the following specification and claims. 75

In the drawings similar characters of reference indicate corresponding parts in the several views.

Fig. 1 is an end view, partly in section, of 80 a picking table unit.

Fig. 2 is an enlarged fragmentary section of the foot control means, taken on the line 2—2 of Fig. 1.

Fig. 3 is an enlarged fragment of the belt, viewed from the side edge. 85

Fig. 4 is an enlarged fragmentary view of an adjustable link or connecting rod construction.

Referring now more particularly to the characters of reference on the drawings, the 90 numeral 1 denotes a standard, supported from the floor, fixed to and projecting horizontally on both sides of which are spaced frames 2, between each pair of which is an endless picking-belt 3, passing at one end 95 over a fixed roller 4, driven by any suitable means over a movable idler roller 5 at the other end.

A common hopper 6 is preferably pro- 100 vided over both belts from which hopper an individual chute 7 leads to each belt, and terminates adjacent the surface thereof, the front of each chute being in the form of a vertically adjustable and flexible flap or 105 gate member 8, the construction and purpose of which is fully set forth in the afore-mentioned patent.

The belts are provided on their upper sur- 110 faces with transverse cleats 9, preferably made of a layer or two of the fabric belt-goods, and consequently very shallow as to depth, and also flexible. In operation of the

device, as the belt moves away from the chute and its gate, a thin layer of nuts or the like is drawn onto the belt from between the belt and gate, the latter giving somewhat to 5 allow the produce to emerge.

As previously stated however, there is a tendency for small sized produce to pack 10 behind the gate, and the action of the cleats on the belt is to strike and break away such pack before it has really assumed the proportions of such. In other words the cleats prevent the formation of a pack, and insure an even and steady flow of the produce onto the belt.

15 At the same time, the size of these cleats is not sufficient to interfere with the operations of the picker at the table.

I will now describe the foot control and 20 automatic belt take-up means. This structure being independent for each belt, it will of course be only necessary to describe one unit.

Slidably mounted on the outside of the frames 2 are plates 10. Near the outer ends 25 of the frames are slots 11, substantially the height of the plates, into which project bearing members 12 fixed onto the plates, and in which the roller 5 is journaled, the slots being sufficiently longer than the bearing 30 to allow for a certain and predetermined longitudinal movement of the bearings and plates.

Extending transversely of the frames thereunder is a shaft 13, preferably beyond 35 the plates, to which latter are flexibly connected links 14, which pass through the shaft 13 and are provided with adjusting nuts 15 on both sides of the shaft.

Rigid links 16 are flexibly connected to 40 the shaft and to the frames 2 extending in a direction opposite to that of the links 14. By means of this construction, the actual operative length of the links 14 may be varied independently of each other, which causes 45 the adjacent plate and end of the roller 5 to be moved accordingly, counteracting any looseness of the belt on one side or the other.

Flexibly connected to the shaft 13 and 50 projecting vertically on both sides of the frames 2 are rods 17 passing through fixed guide brackets 18, said rods having springs 19 thereon bearing at their lower ends on the brackets, and whose tension is adjustable by means of adjusting nuts 20 on the rods 55 above the springs. It will thus be evident that the action of these springs is to force the plates outwardly and to thus tighten the belt, the degree of tautness of which depends on the tension of the springs, which is governed 60 by manipulation of the nuts 20. These springs then automatically take care of the natural stretching or shrinking of the belt, and besides govern the amount of pressure necessary to draw the plates back 65 and release the belt from the driving-fric-

tion with the roller 4, the amount of such pressure and normal belt tension desired or necessary depending on the kind of produce being picked.

The plates are drawn back by pulling 70 down on the shaft 13 which is accomplished by means of a bracket 21 flexibly hung on said shaft intermediate its ends, to which bracket is mounted, for vertical adjustment by means of a nut 22^a, the upper end of a 75 rod 22, the lower end of which is pivoted to a horizontally disposed foot lever 23 having on one end a foot pad 24 and on the upper edge of the other end a plurality of V-shaped notches 25, any one of which is engaged by a knife-edge bearing 26 formed on a plate 27, which is also provided with a rigid catch member 28 adapted to hold the lever against upward movement after the latter is depressed and shifted slightly to one 85 side with the foot.

By reason of the notches and knife-edge bearing construction, a simple means is had whereby the operative length of the lever, from the fulcrum point to the foot-pad end, 90 may be easily and quickly varied to suit the convenience of different operators; since it will be evident that as the fulcrum is moved nearer the connection with the rod 22, a greater movement of the foot pad end of 95 the lever must be had for a certain downward movement of the rod than if the fulcrum point was moved further from the rod connection. It will also be noted that the springs 19 constantly act to hold the members 100 25 and 26 in contact.

The connection of the members 14, 16, 17 and 21 with the shaft 13 are all such as to allow for a certain amount of movement of the shaft away from a true horizontal transverse plane, so as to allow for the taking 105 up of one of the links 14 or springs 20 more than the other, for the purpose as previously set forth, and which of course will have the effect of placing the shaft out of 110 plumb.

By adjusting the nut 22^a, the pad end of the lever 23 may be raised or lowered, thus allowing for the operating end of this 115 lever being positioned at different levels to suit different operators, and independent of any change made in the point of fulcrum of the lever, which has the effect of changing the level of the pad somewhat.

From the foregoing description it will be 120 readily seen that I have produced such a device as substantially fulfills the objects of the invention as set forth herein.

While this specification sets forth in detail the present and preferred construction 125 of the device, still in practice such deviations from such detail may be resorted to as do not form a departure from the spirit of the invention, as defined by the appended claims.

Having thus described my invention, what I claim as new and useful and desire to secure by Letters Patent is:

1. A picking table structure comprising an endless belt, a driven roller at one end of the belt over which the latter passes, another roller at the other end of the belt slidably mounted for movement in a plane parallel to the length of the belt, and foot actuated means for moving the last named roller. 5
2. A picking table structure comprising an endless belt, a driven roller at one end of the belt over which the latter passes, another roller at the other end of the belt slidably mounted for movement in a plane parallel to the length of the belt, foot actuated means for moving the last named roller, and means for automatically taking care of any stretch or shrinkage of the belt. 15
3. A picking table structure comprising an endless belt, a driven roller at one end of the belt over which the latter passes, another roller at the other end of the belt slidably mounted for movement in a plane parallel to the length of the belt, foot actuated means for moving the last named roller and adjustment means for taking care of any unevenness of stretch or shrinkage of the belt at one edge or the other without interfering with the operation of the movement control means. 25
4. A picking table structure comprising an endless belt, a driven roller at one end of the belt over which the latter passes, another roller at the other end of the belt slidably mounted for movement in a plane parallel to the length of the belt, foot actuated means operatively connected to the last named roller at each end for moving the same, and independent means interposed in each such roller, connecting means for taking care of any unevenness in the stretch or shrinkage of the belt at one edge or the other. 35
5. A picking table structure comprising an endless belt, a driven roller at one end of the belt over which the latter passes, another roller at the other end of the belt slidably mounted for movement in a plane parallel to the length of the belt, a transverse shaft under the belt, links flexibly connected to the shaft and operatively connected to the last named roller at each end thereof, other links similarly connected to the shaft and pivoted at fixed points at their outer ends, said last named links extending in a direction substantially opposite to the first named links, means for altering the operative length of one pair of said links individually, and means for moving the shaft vertically. 50
6. A picking table structure comprising an endless belt, a driven roller at one end of the belt over which the latter passes, 55
7. A picking table structure comprising an endless belt, a driven roller at one end of the belt over which the latter passes, another roller at the other end of the belt slidably mounted for movement in a plane parallel to the length of the belt, a transverse shaft under the belt, links flexibly connected to the shaft and operatively connected to the last named roller at each end thereof, other links similarly connected to the shaft and pivoted at fixed points at their outer ends, said last named links extending in a direction substantially opposite to the first named links, rods connected to the shaft and projecting intermediate the link members, spring means on the rods acting to keep the belt in tension, and means for moving the shaft vertically against the tension of the springs, whereby to slacken the belt. 60
8. A picking table structure comprising an endless belt, a driven roller at one end of the belt over which the latter passes, another roller at the other end of the belt slidably mounted for movement in a plane parallel to the length of the belt, a transverse shaft under the belt, links flexibly connected to the shaft and operatively connected to the last named roller at each end thereof, other links similarly connected to the shaft and pivoted at fixed points at their outer ends, said last named links extending in a direction substantially opposite to the first named links, rods connected to the shaft and projecting intermediate the link members, individually adjustable spring means on the rods, said spring means tending to raise the shaft and force the slidably mounted roller away from the fixed roller, and means for drawing the shaft down against the tension of the springs. 65
9. In a belt control device, an endless belt, a fixed roller and a movable roller over which the belt passes, a vertical rod, means between the rod and movable roller whereby the latter will be moved horizontally with a vertical movement of the rod, and means for so moving the rod. 70
10. In a belt control device, an endless belt, a driven roller at one end of the belt over which the latter passes, 75

4
belt, a fixed roller and a movable roller over which the belt passes, a vertical rod, means between the rod and movable roller whereby the latter will be moved horizontally with a 5 vertical movement of the rod, a substantially horizontal foot lever to which the rod is connected, and a fixed member on which the lever is fulcrumed the point of fulcrum with respect to the rod connection with the lever 10 being alterable at will.

11. In a belt control device, an endless belt, a fixed roller and a movable roller over which the belt passes, a vertical rod, means between the rod and movable roller where- 15 by the latter will be moved horizontally with a vertical movement of the rod, a substan- tially horizontal foot lever to which the rod is connected, said lever having a plurality of notches in the upper edge of the lever, 20 and a fixed knife-edge bearing member adapted to engage any one at a time of said notches whereby to form a fulcrum for the lever.

12. In a belt control device, an endless belt, a fixed roller and a movable roller over which the belt passes, a vertical rod, means between the rod and movable roller whereby the latter will be moved horizontally with a 25 vertical movement of the rod, a substan- tially horizontal foot lever to which the rod is connected, said lever having a plurality of notches in the upper edge of the lever, 30 a fixed knife-edge bearing member adapted to engage any one at a time of said notches, 35 and spring means acting to constantly hold

said bearing and the respective notch in contact.

13. In a belt control device, an endless belt, a fixed roller and a movable roller over which the belt passes, a vertical rod, 40 means between the rod and movable roller whereby the latter will be moved horizontally with a vertical movement of the rod, a substantially horizontal foot lever to which the rod is connected, intermediate the ful- 45 crum and foot-pad end of the lever, and adjusting means for altering the operative length of the rod, whereby the vertically level of the foot-pad end of the lever may be altered.

14. In a belt control device, an endless belt, a fixed roller and a movable roller over which the belt passes, a vertical rod, means between the rod and movable roller whereby the latter will be moved horizontally with a 50 vertical movement of the rod, a substan- tially horizontal foot lever to which the rod is connected, intermediate the fulcrum and foot-pad end of the lever, means whereby the 55 point of fulcrum of the lever with respect to the point of connection of the rod there- with may be altered, and independent ad- justing means for altering the operative length of the rod, whereby the level of the 60 foot pad end of the lever may be altered or maintained regardless of alteration of the 65 fulcrum point of the lever.

In testimony whereof I affix my signature.

ARCHIBALD R. STEPHEN.
